PONTIC TOOTH

Winthrop C. Whittemore, New York, N. Y., assignor to The Dentists' Supply Company of New York, New York, N. Y., a corporation of New York

Application October 15, 1936, Serial No. 105,680

1 Claim. (Cl. 32—10)

This invention relates to a pontic tooth, and has particular reference to a pontic tooth incorporating a bulk of porcelain adaptable for root or saddle contact with the tissues, and a lingual incisal area of porcelain.

The primary object of the invention is to provide a pontic tooth having a bulk of porcelain in the gingival area of sufficient size to allow for proper adaptation to the tissues, and having a lingual incisal area of porcelain so shaped as to allow for proper adjustment to antagonizing teeth without weakening the porcelain structure.

Another object of the invention is to provide a pontic having the foregoing features while still providing sufficient area for the frame of the bridge work to which the pontic is attached.

In providing a porcelain tooth having the characteristics above set forth difficulty arises because of insufficient space for proper shape of the lingual incisal area without sacrificing strength.

According to the invention the porcelain pontic tooth may be of the saddle or root type having a pin ledge area with metal pins extending therefrom and a lingual incisal area of porcelain. This description places the pins which extend out of the pin ledge between two areas of porcelain projecting lingually, which areas are flat on the surfaces facing the pins, and are known as "gingival floor" and "incisal floor" respectively. The incisal ledge has an arcuate connection with the pin ledge in order to provide strength and prevent breaking of the lingual incisal area.

The drawing illustrates an embodiment of the invention and the views therein are as follows:

Figure 1 is a front elevation of an upper central incisor.

Figure 2 is a vertical sectional view taken on the line 2—2 of Figure 1, and

Figure 3 is a rear elevational view of the tooth shown in Figure 1.

While the drawing illustrates an upper central incisor, it will be understood that this invention applies to all anterior tooth forms.

Referring now to Figure 2, the pontic tooth is provided at its gingival end A with a bulk of material 6 which may be altered by the dental technician to form either a saddle or root type contact. This pontic tooth has an overhanging part 7 which provides a gingival floor 8 extending lingually from a pin ledge 9. This pin ledge

is provided with pins 11 for anchorage to the bridge frame.

The invention contemplates that the lingual incisal area 12 shall be formed to best represent natural tooth construction or anatomy, and in order that perfect articulation may be obtained with the opposing teeth, one of which is shown in dotted lines and characterized 13.

The pontic is provided with an incisal floor 14 extending lingually, and said floor merges into the pin ledge 9 by an arcuate surface 16. This arcuate surface has a radius approximately one-half the length of the incisal floor to provide sufficient material through the point 18, so that the structure will resist normal forces.

If desired the gingival floor 8 may have an arcuate connection with the pin ledge 9, and this has been indicated by dotted lines at 17. The purpose of providing this last mentioned arcuate surface is to assist in the delivery of "biscuits" from molds during the manufacturing of the porcelain tooth. Both the arcuate surfaces 16 and 17 assist the dental technician in the preparation of the bridge frame, as will be readily understood by those familiar with the art. With this form of tooth the metal frame will not extend to the incisal edge 19, which is an objectionable feature because of its unnatural appearance. The lingual incisal area will give an appearance of natural teeth and the contact with opposing teeth will be porcelain.

Of course, the pontic tooth illustrated and herein described may be modified and changed in various ways without departing from the invention herein set forth and hereafter claimed.

The invention is hereby claimed as follows:

A porcelain pontic tooth having a mass of material at the gingival end adaptable for root or saddle contact, a pin ledge, a gingival floor extending lingually from said pin ledge, an incisal floor extending lingually, and an arcuate surface extending from said pin ledge to said incisal floor, the radius of said arcuate surface being approximately one-half the length of the incisal floor so as to provide sufficient material between same and the lingual area to permit grinding of the latter to provide proper articulation with antagonizing teeth.
